POUNDING TOY

Joseph Green, New York, N. Y.

Application December 4, 1953, Serial No. 27,922

Term of patent 14 years

(Cl. D34—15)

To all whom it may concern:

Be it known that I, Joseph Green, a citizen of United States of America, residing at 35—35 35th Street, Long Island City, in the county of Queens and State of New York, have invented a new, original, and ornamental Design for a Pounding Toy, of which the following is a specification, reference being had to the accompanying drawing, forming part thereof.

In the drawing:

Fig. 1 is a front elevational view of a pounding toy showing my new design;

Fig. 2 is a side elevational view thereof; and

Fig. 3 is a perspective view thereof, the pegs on one side being removed for convenience of illustration.

The projectile shown in broken lines in Fig. 1 has been omitted from Fig. 3 for convenience of illustration.

I claim:

The ornamental design for a pounding toy, substantially as shown and described.
